UNITED STATES PATENT OFFICE.

OLIVER S. RIBLET, OF ERIE, PENNSYLVANIA.

CONCRETE-MIXER.

1,111,180.

Specification of Letters Patent. Patented Sept. 22, 1914.

Application filed January 8, 1912. Serial No. 670,032.

To all whom it may concern:

Be it known that I, OLIVER S. RIBLET, a citizen of the United States, residing at Erie, in the county of Erie and State of Pennsylvania, have invented new and useful Improvements in Concrete-Mixers, of which the following is a specification.

This invention relates to concrete mixers, and consists in certain improvements in the construction thereof as will be hereinafter fully described and pointed out in the claim.

The object of the invention is to provide a rotating concrete mixer with compartments whereby a part of the drum may be utilized for mixing while the other part of the drum is discharging.

In the accompanying drawings which form a part of this specification and wherein like numerals designate like parts; Figure 1 is a vertical section of a concrete mixer embodying my invention. Fig. 2 is the discharge end view of the same.

1 designates the drum. This may be of any desired construction.

2 designates the mixing chamber. The material is delivered to this mixing chamber through an opening 17 in the end 2^a of the drum.

3 designates the discharge chamber.

4 The chambers 2 and 3 are separated by the partition 4 having an opening 5, preferably central. A cover 6 is provided for the opening 5. The cover is secured to a sleeve 8, and the sleeve 8 is mounted on a rod 7.

5 The rod 7 is secured in a mounting 9 extending from the walls of the drum to the center and the sleeve 8 extends into a mounting 10 extending from the walls of the drum to the center. The lever 11 is mounted on a

10 post 12 extending upwardly from the platform or frame 14 on which the drum is mounted. The end of the sleeve is secured to the lever 11 so that by swinging the lever 11, the sleeve may be moved axially on the rod 7, thus moving the cover 6 to open and close the opening 5.

The drum is mounted on the usual rollers 13 and is provided with any scheme of driving mechanism (not shown) now in common use.

50 The flights 15 are arranged in the mixing chamber 2. These flights 15 extend inwardly from the circumferential walls of the mixing chamber and are at an

angle to a plane extending through the axis of the drum, the result being to give the flights a downward inclination toward the opening 5 with their upward movement. The flights also preferably have the extension 15^a at the partition end which is arranged to guide the material as it moves along the flights toward the center. When the cover 6 is opened, the material as it is carried up by the flights 15 slides on said flights toward the center and shoots through the opening 5 in the discharge end 3. During the mixing operation, the cover 6 is maintained in a closed position and when the material is sufficiently mixed the cover is opened and the material is with great rapidity thrown into the discharge end of the mixer when the cover may be again closed and a fresh batch delivered to the mixing end of the drum. Flights 16 are arranged in the discharge end of the drum. These are inclined so as to carry the material toward the discharge end of the drum. If desired, the discharge end of the drum may be provided with a spout 18 into which the material drops as it is carried up by the flights 16.

By carrying the cover 6 on a mounting carried directly by the drum the cover when closed has no movement relatively to the partition. This is of particular advantage where the drum has a roller mounting in that the axis of the drum so mounted has more or less movement in directions at right angles to the axis.

What I claim as new is:

In a concrete mixer, the combination of a rotatable drum; rollers operating on the periphery of the drum and forming a mounting for said drum; a partition in the drum having an opening therein; a cover for said opening; and means mounted on the drum for supporting the cover, the cover being slidably mounted relatively to said means, said means maintaining the cover in parallel relation to the partition as it is moved.

In testimony whereof I have hereunto set my hand in the presence of two subscribing witnesses.

OLIVER S. RIBLET.
